UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed March 8, 1921. Serial No. 450,743.

To all whom it may concern:

Be it known that I, FRED S. CARR, a citizen of the United States, and a resident of Newton, in the county of Middlesex and 5 Commonwealth of Massachusetts, have invented an Improvement in Fasteners, of which the following description, in connection with the accompanying drawings, is a specification, like characters on the drawings representing like parts.

This invention pertains to improvements in separable fasteners. It is among the objects of the invention to provide a separable fastener of simple construction, great durability and of superior holding power.

In the drawings, which show a preferred form of one illustrative embodiment of my invention:

Figure 1 is an elevation of two pieces of 20 fabric to which the stud and socket members of a preferred form of separable fastener are attached;

Fig. 2 is a section on the line 2—2 of Fig. 1;

Fig. 3 is a front elevation of the preferred 25 form of socket illustrated in Figs. 1 and 2;

Fig. 4 is an elevation of the preferred form of stud shown in Figs. 1 and 2; and

Fig. 5 is a section through the fastener 30 on the line 5—5 of Fig. 1.

Referring to the drawings and to the preferred form of my invention selected for illustrative purposes, I have shown a stud including a head 6, a neck 7 and a base 8, 35 and secured to the stud-carrying fabric 9 in any suitable way as by stitching 10. I have shown a cooperating socket including a casing 11 providing a stud-receiving plate 12 having a stud-receiving aperture 13

40 therein and containing a spring 14 presenting two portions intersecting the stud-receiving aperture 13. The preferred form of spring will be more fully described hereinafter. The preferred form of socket il-

45 lustrated is sewn to the socket-carrying fabric 15 by stitches 16. Where my invention is utilized in connection with fastening elements adapted to be sewn to their carrying fabrics, I prefer to make the casing 11 in one piece and to provide for holding in

50 the spring 14 by a flanged-over rim 17 of the casing. The stud-receiving aperture 13 is preferably notched at one side providing the recess 18 communicating with the stud-receiving aperture 13 and adapted to per-

mit the stud to shift laterally in the socket to a small extent, sufficient to prevent separation of stud and socket by the resolution of forces arising from lateral strain between stud and socket urging the stud 60 toward the notch, or in the general direction of the notch, the notch, however, preferably being of such dimension relative to the neck and head of the stud that separation of stud and socket may be effected even 65 while under considerable lateral strain by a convenient tipping movement at an angle somewhat greater than that likely to be produced by the resolution of forces arising from lateral strains in the direction indicated.

The spring 14, as above described, preferably intersects the stud-receiving aperture 13 at opposite sides thereof as at 19 and 20. Between these portions, the spring extends 75 adjacent to the peripheral wall of the socket, underlying the flange 17 at 21. At the other side of the portions 19 and 20 the spring underlies the flange 17 at 22 and 23, being

70 bent backwardly and outwardly until they 80 again underlie the flange 17 at the sides of the casing at 24 and 25, these preferably being, as illustrated, adjacent terminal re-

verse bends extending outwardly and downwardly to the ends of the spring at 26 and 85 27. The bends 22 and 23 are preferably spaced away from the marginal wall of the casing so that the resiliency of the spring will not be impaired by bearing against the side of the casing at these points. Simi-

90 larly, the bends at 24 and 25 are also preferably spaced away from the peripheral wall of the casings. The stud-engaging portions 19 and 20 of the spring are prefer-

ably inclined, preferably in part only as 95 illustrated, so as to tend to press or cam the stud toward the notch 18. The inclined portions may be provided by offsets as illus-

trated, or in any other suitable way.

The spring may, if desired, be positioned 100 relative to its casing by a projection 31 extending within the curve of the spring adjacent its central portion 21.

When the head of the stud 6 is entered through the stud-receiving aperture 13 in 105 the casing, the stud-engaging spring jaws 19 and 20 are spread apart and grip the neck 7 of the stud when the latter is fully entered in the socket. The notch 18 in the socket is preferably adjacent the edge 30 of 110

the socket-carrying fabric 15, so that the normal lateral strain between stud and socket will lead the neck of the stud into the notch 18. When the stud is entered in this notch, the resolution of forces arising from lateral strain will not cause the stud to tip in such a way as to become separated from the socket. On the other hand, when it is desired to separate the stud from the socket, a pull on either the stud or socket in either an axial direction or one producing a tip somewhat greater than that arising from the resolution of forces under lateral strain will cause the stud to be released from the socket even though a considerable amount of lateral strain between stud and socket exists at the time of separation.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

Claims.

1. A separable fastener comprising, in combination, a stud having a head and a neck presenting between them a sloping shoulder, and a socket including a casing having a stud-receiving aperture therein and a notch communicating with said aperture, said casing carrying a spring presenting two generally parallelly disposed portions in-

tersecting said aperture, said portions inclined to urge said neck of said stud toward said notch.

2. A socket for a stud and socket fastener, said socket including a casing providing a plate with a stud-receiving aperture therein, and a notch communicating with said aperture, a spring in said casing presenting a portion extending substantially across said socket and intersecting said aperture, said portion disposed to press said neck of said stud toward said notch.

3. A socket for a stud and socket fastener, said socket including a casing providing a plate with a stud-receiving aperture therein, a notch communicating with said aperture, and a spring in said casing presenting portions extending substantially across said socket and intersecting said aperture, said portions disposed to press said neck of said stud toward said notch.

4. In a stud and socket fastener, a socket including a casing having a stud-receiving aperture therein and a W-shaped spring therein, two runs of said spring forming the central portions of the W intersecting said aperture and presenting offset portions intersecting said aperture to press a stud entered through said aperture against that side of the aperture generally opposite said offset portions.

In testimony whereof, I have signed my name to this specification.

FRED S. CARR.
